SAMUEL G. RUSSELL, ERNEST L. BUCHANAN, AND ROSSITER R. POTTER, OF KALAMAZOO, MICHIGAN, ASSIGNORS TO SHAKESPEARE PRODUCTS COMPANY, OF KALAMAZOO, MICHIGAN

BROOM OR THE LIKE

Application filed July 12, 1928. Serial No. 292,143.

The main objects of this invention are to provide an improved broom or brush which is very economical to manufacture in the matter of labor and material entering into the same and at the same time one which is very durable and neat and attractive in appearance.

Objects relating to details and economies of construction and operation of our invention will definitely appear from the detailed description to follow.

The invention is clearly defined and pointed out in the claims.

A structure which is a preferred embodiment of our invention is illustrated in the accompanying drawing, forming a part of this application, in which:

Fig. 1 is a side view of a broom embodying the features of our invention, the handle being partially broken away.

Fig. 2 is a fragmentary section on a line corresponding to line 2—2 of Fig. 1.

Fig. 3 is a fragmentary view on a line corresponding to line 3—3 of Fig. 1.

Fig. 4 is a transverse section on a line corresponding to line 4—4 of Figs. 1 and 2.

Fig. 5 is a fragmentary view partially in section on a line corresponding to line 5—5 of Fig. 3.

Fig. 6 is a fragmentary view illustrating a modified form of the invention.

Fig. 7 is a fragmentary vertical section corresponding to that of Fig. 5 of a modified form or embodiment of our invention.

In the drawing similar reference characters refer to similar parts throughout the several views, and the sectional views are taken looking in the direction of the little arrows at the ends of the section lines.

Referring to the drawing, 1 represents a broom or brush body which is made up of splints of broom corn or suitable fibre as may be desired. As a base or foundation for the body, we provide a head member 2 formed of strands of wire and conformed to provide a helix to engage the threads of a handle. In the embodiment shown in Fig. 5, both strands of wire are coiled to provide helical coils 3 disposed in a superimposed relation, the coils 50 coacting to provide the helix. The strands

are twisted together at each side of these coils 3 and the splints are folded over this head member. The ends 4 of the head member are curved upwardly to embrace opposite edges of the splint body at the fold thereof. 55

The handle 5 has a tapered portion 6 which is screwed into the helix. This may be threaded although satisfactory results are had without previous threading as it may be twisted into the helix, the helix itself forming threads sufficient to retain the handle. 60

In the embodiment shown in Fig. 6, the head member shown at 11 is provided with a single coil 12 to receive the handle. This is found practical for light brushes or brooms 65 where the head member may be made of heavier material than is necessary where there are two strands as is shown in the other embodiments.

In the embodiment shown in Fig. 7, only 70 one of the strands is formed into coils 3 to provide a handle retaining socket.

Below the head member is a band 7 preferably of wire. A U-shaped clamp 10 having a hole in the bight thereof to receive the handle is arranged over the head of the broom to overlap the inturned ends 4 of the head member. 75

The head clamp member 10 in the embodiment illustrated is arranged with its lower 80 ends below so as to be embraced by the band 7. It may however be arranged above the band, the object being to provide a co-engaging relation for these parts.

Cross ties 8 are arranged through the fibre 85 to engage this band 7, there also being a loop-like cross tie 13 arranged through the lower ends of the clamping head member 10 and in a horizontal relation so that the tip of the handle projects between the members of this cross tie although not engaged thereby. This further supports the handle and effectively clamps the fibre at the point where the same is engaged by the handle so that the handle 90 is not likely to work sidewise in the fibre. 95

The clamp serves to prevent the fibres working up above the head and the band serves to hold the clamp down so that the folded fibres are very securely retained in position, and at 100

the same time the means for securing is very simple and easily applied.

The broom may be provided with stitching

9. Whether or not this stitching is used depends on the length of the fibre or splints. Ordinarily, satisfactory brooms and brushes can be made without this stitching as the splints are very securely clamped and retained by the means described.

10. Our improved brush is very economical to produce, both in the matter of material and labor and the completed brooms or brushes are very strong and durable.

Having thus described our invention, what 15 we claim as new and desire to secure by Letters Patent, is:

1. An implement of the class described comprising a head member formed of strands of wire having helical coils therein providing a helix adapted to receive a handle, the strands being twisted together at each side of the helix and having their ends upturned, fibres folded over said head member, the upturned ends of the head member being 25 clamped upon the folded fibres, a U-shaped clamping member arranged over the fold of the fibres to engage the ends of said head member, a clamping band disposed below said head member in coengaging relation with 30 the lower ends of said clamping member, said clamping member having a hole therein to receive the handle, and tie members arranged through the fibres to engage opposite sides of said band, one or more of said tie members 35 being arranged through the ends of said clamping member.

2. An implement of the class described comprising a head member, fibres folded over said head member, said head member having 40 inturned ends engaging and overlapping the fold of the fibres, a U-shaped clamping member arranged over the fold of the fibres to engage the ends of said head member, a clamping band disposed below said head member, and tie members arranged through the fibres to connect the opposed sides of the band and the ends of said clamping member.

3. An implement of the class described comprising a head member provided with a 50 handle socket, fibres folded around and secured around said head member, a U-shaped clamping member arranged over the fold of the fibres, a band embracing the fibres below said head member in coengaging relation with said clamping member, and tie members disposed through the body of the fibre connecting opposite sides of the band member and clamping the same upon said clamping member.

4. An implement of the class described comprising a head member provided with a handle socket, fibres folded over said head member, said head member having upturned 60 and inturned ends in overlapping clamping

engagement with the fold of the fibres, and a U-shaped clamping member arranged over the fold of the fibres to engage the ends of said head member, said clamping member having a hole therein to receive a handle.

5. An implement of the class described comprising a head member, fibres folded over said head member, said head member having upturned and inturned ends in overlapping clamping engagement with the fold of the fibre, and a U-shaped clamping member arranged over the fold of the fibres to engage the ends of said head member.

6. An implement of the class described comprising a head member formed of strands of wire having helical coils therein disposed in superimposed relation providing a helix adapted to receive a handle, the strands being twisted together at each side of the helix and having their ends upturned, 85 fibres folded over said head member, and a clamping band of wire disposed below said head member, the opposite sides of said band being connected together at intervals by ties disposed through the fibres.

7. An implement of the class described comprising a head member formed of strands of wire, one of which has helical coils therein providing a helix, the strands being twisted together at each side of the helix 95 and having their ends upturned, fibres folded over said head member between its said upturned ends to surround said helix, the upturned ends of said head member being folded upon said fibers and independent of said helix, and a handle threaded into said helix.

8. An implement of the class described comprising a head member formed of strands of wire, one of which has helical coils therein providing a helix adapted to receive a handle, the strands being twisted together at each side of the helix and having their ends upturned, and fibres folded over said head member between its said upturned ends to surround said helix, the upturned ends being clamped upon the opposite edges of the body of fibres at the fold thereof.

9. An implement of the class described comprising a head member formed of strands of wire at least one of which is conformed to provide a helical handle socket, fibres folded over said head member, the ends of said head member being upturned and clamped upon the folded fibres, a U-shaped clamping member arranged over the folded fibres to engage the ends of said head member, a clamping band disposed below said head member in coengaging relation with the lower end of said clamping member, a cross tie having spaced side members arranged through the lower ends of said head member in alignment with said handle socket, and a handle disposed in said handle socket with its lower 125 end.

end projecting between the side members of said cross tie.

10. An implement of the class described comprising a head member formed of strands of wire at least one of which is conformed to provide a helical handle socket, said head member having bendable ends, fibres folded over said head member, the ends of said head member being upturned and clamped upon the folded fibres, a U-shaped clamping member arranged over the folded fibres to engage the ends of said head member, a cross tie having spaced side members arranged through the lower ends of said head member in alignment with said handle socket, and a handle disposed in said handle socket with its lower end projecting between the side members of said cross tie.

11. An implement of the class described comprising a head member provided with a handle socket, said head member having bendable ends, fibres folded over said head member, the ends of said head member being upturned to clamp the folded fibres, a U-shaped clamping member arranged over the folded fibres to engage said head member, a clamping band disposed below said head member in coengaging relation with the lower end of said clamping member, a cross tie having spaced side members arranged through the fibres below said handle socket, and a handle disposed in said handle socket with its lower end projecting between the side members of said cross tie.

35 12. An implement of the class described comprising a head member provided with a handle socket, said head member having bendable ends, fibres folded over said head member, the ends of said head member being upturned to clamp the folded fibres, a U-shaped clamping member arranged over the folded fibres to engage said head member, a cross tie having spaced side members arranged through the fibres below said handle socket, and a handle disposed in said handle socket with its lower end projecting between the side members of said cross tie.

40 13. An implement of the class described comprising a head member formed of strands of wire one of which has a coil therein providing a handle socket, a substantial flat body of fibres folded over and secured upon said head member to surround said handle socket coil, the ends of the head member being conformed to embrace opposite edges of the fibre body, and a handle threaded into said socket.

45 14. An implement of the class described comprising a head member of wire having a coil therein providing a handle socket, and a substantial flat body of fibres folded over said head member to surround said handle socket coil, the ends of said head member being clamped upon opposite edges of the body of folded fibres.

In witness whereof we have hereunto set our hands.
